ABSTRACT: A modular logic unit consisting of a plurality of identical logic elements interconnected to perform a large variety of arithmetic operations which fully utilize the logic elements so as to make efficient use of the logic elements and to maintain the cost of such unit at a minimum. An arithmetic unit composed of a plurality of such modular units and a plurality of associated storage registers, there being one modular unit associated with each bit location of the storage registers.

MODULAR UNIT FOR DIGITAL ARITHMETIC SYSTEMS

BACKGROUND OF THE INVENTION

The present invention relates to a modular logic unit consisting of electronic switching means and having four inputs each one of which receives an operand consisting of binary electrical signals and four outputs for such signals.

In the construction of complex electronic digital circuits for use, for example, in the electronic computer art, it is highly desirable, if not absolutely necessary, for reasons of economy and to permit more standardized systems engineering procedures, to limit the number of different modular units, a modular unit being a group of basic logic elements combined into a functional unit.

The limitation on the total number of different types of modular units which would satisfy the requirements of any computing system is, however, restricted at the lower end by economic considerations because as the number of functions which one modular unit can perform increases, its utilization factor generally decreases.

SUMMARY OF THE INVENTION

It is a primary object of the present invention to substantially reduce these drawbacks and difficulties.

Another object of the invention is to substantially reduce the cost of modular units having a highly flexible operation.

Yet another object of the invention is to substantially reduce the number of different elements required for such a modular unit.

Yet a further object of the invention is to make maximum use of the logic elements of a modular unit in the performance of various logic operations.

Still another object of the invention is to simplify the structure of such modular units.

These and other objects according to the invention are achieved by the provision of a modular logic unit composed of a plurality of identical logic elements interconnected to have four inputs, X, Y, Z, and c each arranged to receive one binary bit having a value of "1" or "0," and four outputs R, S, T and C. The elements are interconnected for causing the output R to present a binary "1" only when the modulo-2 sum of the bits delivered to inputs X, Y and Z is a binary "1," output S to present a binary "1" only when the modulo-2 sum of the bits delivered to all four inputs is a binary "1," the output T to present a binary "1" only when the bits delivered to at least two of the inputs X, Y and Z have a value of "1," and output C to present a binary "0" only when a binary "0" appears at each of the inputs X, Y and Z, or a binary "1" appears at only one of the four inputs, or a binary "1" appears only at each of the inputs X, Y and Z.

The objects according to the invention are also achieved by the provision of an n-bit arithmetic unit composed of a plurality of such logic units, with each of the logic units being associated with a respective bit location of the arithmetic unit.

The present invention therefore provides a modular unit which has particularly favorable properties especially when used as a circuit component in a digital computer, which circuit component can be constructed without increased expenditures while being capable of performing any one of a plurality of diverse functions.

The unit according to the invention further makes possible the performance of a rapid succession of multistate functional steps.

BRIEF DESCRIPTION OF THE DRAWINGS

FIG. 1 is a block diagram of the modular unit of the present invention and a representation of its functions.

FIG. 2 is a block diagram of one system employing the modular unit according to FIG. 1.

FIG. 3 is a block diagram of a modified version of the arrangement according to FIG. 2.

FIG. 4 is a simplified diagram illustrating a portion of another modification of the arrangement according to FIG. 2.

FIG. 5 is a simplified block diagram of an arithmetic unit constructed of modular units according to the present invention.

FIG. 6 is a block diagram of one preferred embodiment of the modular unit according to the invention.

FIG. 7 is a circuit diagram of a basic logic element of the circuit of FIG. 6.

In all of the figures the same components bear identical reference numerals.

DESCRIPTION OF THE PREFERRED EMBODIMENTS

FIG. 1 shows a basic logic modular unit 1 according to the invention. It has four inputs Y, Z and c and four outputs R, S, T and C. The binary input and output signals of the modular unit 1 might be identified according to the terminals (inputs or outputs) at which they appear. Thus, the logic description of the operation of the modular unit 1 can be stated as follows:

$$\begin{aligned} R &= X \oplus Y \oplus Z \\ S &= X \oplus Y \oplus Z \oplus c \\ T &= (X \cdot Y) \vee (X \cdot Z) \vee (Y \cdot Z) \\ C &= c \cdot (X \oplus Y \oplus Z) \vee \overline{(X \oplus Y \oplus Z)} \cdot (X \cdot Y \vee X \cdot Z \vee Y \cdot Z) \end{aligned}$$

where: $\oplus$ represents a modulo-2 addition (e.g. $a \oplus b = \overline{a} \cdot b \vee a \cdot \overline{b}$);

$\vee$ represents a disjunction, or OR function, and is equivalent to the symbol "+" commonly used in the computer field; the "-" represents a conjunction or AND function, and is equivalent to the symbol "x"; and a bar over a term is the logic representation of a negative, or

30 NOT function.

The modular unit producing the above combination of the four functions for R, S, T and C according to the present invention makes possible a plurality of operations which will be individually described below in connection with the drawings together with their advantageous interaction within the framework of the present invention.

In FIG. 2 the modular unit 1 is augmented by three controllable circuits 2a, 2b and 2c to constitute a unit 2 having the inputs X' , Y' , Z' and c_i , the subscript i indicating that this is the i th stage of a multistage assembly. Each one of the controllable circuits has an input, an output and two control inputs. The input of circuit 2a is connected to the input X' of the unit 2 and its output to the input X of the modular unit 1. Similarly, the two circuits 2b and 2c are disposed between the inputs Y' and Y or Z' and Z , respectively. Control signals are applied to the control inputs of each of the above-mentioned circuits via a respective double line 2a1, 2b1 or 2c1, each shown here as a single line, in response to which they either transfer the offered input signal, either directly or inverted, to the modular unit 1, or they transmit a logic 0 to 1 signal, independent of the input signal. Thus, the use of primes herein only indicates that an output can be, but is not necessarily, different from its associated input. This arrangement therefore permits the operands which are to be combined to be presented to the modular unit either directly or in inverted form, or permits individual ones of the inputs X, Y and Z to be set to 0 or 1. The input c_i is identical with the input c of FIG. 1.

The input X'_i of unit 2 is connected to the output d_i of a memory element D_i . The input Y'_i is similarly connected to the output a_i of a memory element A_i , and the input Z'_i is connected to the output u_i of a memory element U_i . At the other side of the unit, the output R_i is connected to the input b_{i11} of a memory element B_{i11} , the output S_i is connected to input b_i of a memory B_i , and the output T_i is connected to the input v'_i of a memory element V_i . The outputs R_i , S_i and T_i are identical with the outputs R, S, and T of FIG. 1.

In the following description, the designation of the output of a memory element simultaneously indicates its contents, i.e., the operand stored therein. Memory element B_{i11} thus receives the modulo-2 sum of d_i , a_i and u_i , memory element B_i receives the modulo-2 sum of d_i , a_i , u_i and c_i , and memory element V_i is set to 1 when the function $T = a_i \cdot d_i \vee d_i \cdot u_i \vee a_i \cdot u_i$ is satisfied, or true. If one of the inputs X, Y or Z is 0, a conjunction, i.e., an AND function, is formed, via output T_i ,

between the other two interconnected input memory element contents, e.g. if $Y = 0$, $T_i = d_i \cdot u_i$, and by setting the same input to 1 their disjunction or OR function is formed, e.g. if $Y = 1$, $T_i = d_i \vee u_i$.

If at least one of the three operands d_i , a_i and u_i is made ineffective by means of the circuits 2a-2c, the respective circuit will emit a signal representing 0 and the output C_i will furnish the carryover and the output S_i the sum, of a dual addition between the addends d_i , a_i and c_i , or d_i , u_i and c_i , or a_i , u_i and c_i . The addend c_i can then be the carryover C_{i+1} from another digit, or bit location, of a multidigit addition.

It is thus possible to add three operands with the modular unit 1 according to the present invention as long as it is assured that one of the three operands is 0. This condition can be met for example, by means of the circuits 2a-2c or, in an electronic computer, by an appropriate program.

The output T_i emits, in such an operation, a carryover for one particular bit, i.e., the carryover from the addition of the two addends without being affected by the carryover from another bit location which has been brought in via input c_i .

When the condition is met that two of the three inputs X , Y and Z are held at 0, via the circuits 2a-2c, transfer operations can be performed via output R_i . For example, the memory element B_{i+1} will accept the contents of memory element A_i , when the outputs of circuits 2a and 2c are held at logic 0 by their respective control lines 2a1 and 2c1, and when circuit 2b is set to transfer without inverting its input.

It is further possible, by means of the modulo-2 addition, to perform coincidence tests between two operands.

In order that, during multistage arithmetic or combining operations, the contents of the memory elements B_{i+1} , B_i and V_i , which contents constitute the results of the respective previous operations, need not, before any further operation is initiated, be first transferred into the memory elements D_i , A_i and U_i , which latter elements are in communication with the inputs X'_i , Y'_i and Z'_i , of unit 2, an arrangement is provided, as shown in FIG. 3, for the memory elements, except for D_i , to be connected selectively either via their inputs or via their outputs to the unit 2.

It is particularly possible to connect the output of either one of the memory elements A_i and B_i , via a switch 31, to the input Y'_i . The output R_i is selectively connected, via a switch 32, either to input b'_{i+1} of memory element B_{i+1} , or to the input a'_{i+1} of a memory element A_{i+1} , and output S_i is selectively connected, via a switch 33, either to the input a'_i of memory unit A_i , or to the input b'_i of memory unit B_i .

The switches 31-33 are switched simultaneously, and in the same direction, so that it will never occur that one memory element is simultaneously connected to both an input and an output of unit 2. Correspondingly, memory elements U and V can have their respective outputs u_i and v_i connected to the input Z'_i , via a switch 41, and their respective inputs u'_i and v'_i connected to the output T_i of unit 2 via a simultaneously operated switch 42.

Switches 31-33, 41 and 42, as well as circuits 2a1, 2b1 and 2c1, are preferably controlled, when unit 2 is used in a digital computer, by a suitable microprogram control unit.

The above-mentioned switches are preferably electronic switches which, when used in fast-acting switching circuits, have a signal transmission delay time which is not negligible. This is added to the signal transmission delay time of unit 2. If the effect of the signal delay times due to the switches are to be eliminated, an arrangement of the type shown in FIG. 4 must be employed. It consists of two identical units 21 and 22, each corresponding to a unit 2, of the type shown in FIG. 2 with the memory elements shown there. However, to simplify the illustration only memory element A_i and B_i are shown here. For the same reason only one of the inputs, i.e. Y'_{21} or Y'_{22} , respectively, and one of the outputs S_{21} or S_{22} , respectively, are shown at each unit. The output S_{21} of unit 21 leads to input a'_i of memory element A_i , output a_i of this memory element leads to input Y'_{22} of unit 22, the output S_{22} of unit 22 is connected to input b'_i of memory element B'_i , and the output b_i of element B'_i leads to input Y'_{21} of unit 21. In a multistage combining process, units 21 and 22 are activated alternately and, correspondingly, the respective intermediate results are

stored alternatingly in memory elements A_i and B_i . Activation of both units occurs via their respective control lines, here represented by sets of three arrows.

Before the circuit unit of FIG. 3 is further described, a register word will be defined: A register word may be the contents $a_n, \dots, a_i, a_{i+1}, \dots, a_0$ of an operand register A consisting of register elements $A_n, \dots, A_i, A_{i+1}, \dots, A_0$. If the bits of the register word are weighted, a_0 will have the lowest value and a_n the highest. Correspondingly, the memory elements in FIGS. 2 10 and 3 can each be a register element of an operand register. D_i is then, in particular, the i th register element of an operand register D, A_i is the i th register element of an operand register A, etc., A_{i+1} is the $(i+1)$ th register element of operand register A and B_{i+1} is the $(i+1)$ th register element of operand register B. 15 Unit 2 accordingly becomes the i th arithmetic circuit of an n -digit arithmetic unit.

It should here be particularly noted that output R_i differs from the other outputs in that it does not lead to the inputs of the i th register elements, but rather to those of the $(i-1)$ th register elements. Thus, the result appearing at R_i is shifted to the right by one digit, or bit location, and is transferred into one of the operand registers A or B, respectively. If the result appearing at R_i is merely the contents of an operand register connected to its input, a register shift to the right by one bit location will thus occur.

A complete arithmetic unit based on the circuitry of FIG. 3 is shown in FIG. 5. While the circuit of FIG. 3 was described as the i th arithmetic circuit of an arithmetic unit, the arithmetic 30 unit shown in FIG. 5 is constituted by a plurality of the circuits of FIG. 3.

The arithmetic unit consists of $(n+1)$ arithmetic circuits $2_n, \dots, 2_{i+1}, 2_i, 2_{i+1}, \dots, 2_0$, one for each word bit location, with a set of switches 31, 32, 33, 41, and 42, associated with each 35 bit location. For purposes of clarity, however, only the switches of the i th digit are shown as is their connection to the i th register element of each of the operand registers D, A, B, V and U. A further, shiftable operand register MQ is provided whose shift input mg' is connected to the output R_0 of the unit 40 2₀. Particularly during a computation involving double word length results, e.g. during multiplication, the operand register MQ will accept one-half of the double word length result.

In order to assure that the register elements of the operand registers A and B will not be simultaneously controlled by two 45 arithmetic circuits, e.g. the register element a_i by S_i and R_{i+1} , two further switching means are preferably provided by which the outputs R_i and S_i of each unit 2, can be interconnected or disconnected. These switching means, however, are not shown in FIG. 5.

50 The functions described for the circuits of FIG. 1 to 3 are also applicable for the arithmetic unit of FIG. 5. The latter makes possible the conjunctive digital combination of the contents of two registers, which is significant, for example, for mask operations, and it also makes possible the disjunctive digital combination, the modulo-2 sum, between 1 to 3 register contents and the formation of the dual sum (outputs S) between the contents of three operand registers. In this latter case, provision must be made, by means of macro- or micro-programming measures, for example, that the contents of one 55 of the three operand registers, either for each bit location or entirely, must always be 0.

The advantageous utilization of the R and T outputs, in particular, results in a multiplication procedure which is favorable with respect to the requirements of the microprogram and to time.

60 Several basic computing operations as performed by an arithmetic unit according to the invention will now be described by way of example.

MULTIPLICATION

Multiplication is performed in the conventional manner as far as the basic procedure is concerned, i.e., in any i th multiplication step, the multiplicand is added or not added, depending on whether the i th bit of the multiplier is a 1 or a 0, to

the result of the preceding multiplication step, after the latter result has been shifted one bit location to the right. Furthermore, the multiplicand, in a known manner, remains unchanged in one operand register (here in the operand register (D) during the entire multiplication process and the multiplier in the shiftable operand register MQ (multiplicand-quotient register) is reduced by one bit with each multiplication step whereas the right portion of the ultimate double word length product is built up therein in the same manner.

A preferred multiplication procedure according to the present invention is achieved according to the following sequence:

0th step $m_0 \cdot \langle D \rangle, \langle A \rangle, \langle V \rangle_{T \rightarrow U}^{R \rightarrow B}$

1st step $m_1 \cdot \langle D \rangle, \langle B \rangle, \langle U \rangle_{T \rightarrow V}^{R \rightarrow A}$

kth step $m_k \cdot \langle D \rangle, \langle A \rangle, \langle V \rangle_{B \rightarrow U}^{R \rightarrow B}$

nth step $m_n \cdot \langle D \rangle, \langle B \rangle, \langle U \rangle_{T \rightarrow V}^{R \rightarrow A}$

(n+1)th step $U \cdot \langle D \rangle, \langle A \rangle, \langle V \rangle_{T \rightarrow U}^{R \rightarrow B}$

where:

m_k = kth digit of the multiplier (which determines the signals on control lines 2a1)

$\langle \rangle$ = contents of one operand register, such as $\langle D \rangle$ equals content of operand register D, etc.

$\underline{R}$ = The intermediate results at the R outputs of the arithmetic unit are shifted one bit location to the right, except for the value at R_0 , and is transferred into the operand register listed to the right of this symbol, i.e., in step 0 it is shifted into the operand register B, in step 1 into A.

$\underline{T}$ = The partial intermediate results at the T-outputs of the arithmetic unit are transferred to the operand register listed to the right of the symbol.

These steps may be described more fully as follows:

At the beginning of a multiplication process, the contents of operand registers A, B, V and U are set to zero.

0 Step

The multiplicand $\langle D \rangle$ is applied to the X' inputs of the arithmetic unit when the lowest-valued digit m_0 of the multiplier equals 1. The outputs of the operand register A are connected to the Y' inputs and the outputs of operand register V are connected to the Z' inputs. The values derived therefrom are transferred, as described above, to the operand registers B and U. The values R, here form the dual digital sums, and the values T, the digital carryovers of the input operands. These carryovers are considered in the next (first) step.

First Step

Depending on m_1 , the operand register D is connected to the X' inputs. The operand register B is now connected to the Y' inputs, the operand register U to the Z' inputs. The operand register A is connected to the R outputs, the operand register V to the T outputs. Due to the register change, the original output registers have now become input registers and vice versa (with the exception of D). In this step, the carryovers from the preceding step are also taken into consideration.

(n+1)th Step

In this step, only the carryovers from the nth step are being computed.

The above-described multiplication procedure fully utilizes the advantages of the arithmetic unit according to FIG. 5. The shift pulse required after each addition in the known arithmetic units is eliminated and the addition periods are reduced, due to the elimination of the time otherwise required for the circulating carryovers (the sum outputs S_i and carryover outputs C_i are not being used), to the switching time of the 2₁ units and the other required transfer times.

10

DIVISION

Division is accomplished according to the known subtraction method in which a 1 is entered into the quotient when the difference becomes positive after subtraction of the divisor

15 from the intermediate remainder. It is known to accomplish this procedure in such a manner that the divisor is again added to a negative difference and the thus resulting sum is multiplied by 2 (shift to the left) and serves as minuend in the next stage of the multiplication process. In the arithmetic unit 20 shown in FIG. 5, however, the negative difference which can be recognized from the presence or nonpresence of the carryover C_n is not transferred by the arithmetic unit into an operand register. Rather, the still existing minuend which leads to a negative difference (e.g. present in operand register 25 A or B) is immediately shifted by one register (multiplication by 2) and the next subtraction is initiated (next arithmetic step). In this manner, the time required in the known division process to recover the minuend when negative differences occur is saved.

30 FIG. 6 shows a practical embodiment of a modular unit according to the present invention as illustrated in FIG. 1 and of the unit 2 according to the present invention as illustrated in FIG. 2. The modular unit 1 consists of five identical known logic elements 11, 12, 13, 14 and 15.

35 Each logic element has four inputs e, f, g and h and two outputs s and $\bar{s}$. The output signals are related to the input signals as follows:

$$\bar{s} = (e \vee f) \cdot g \vee h$$

40 and

$$\bar{s} = \bar{e} \cdot \bar{f} \vee \bar{g} \cdot \bar{h}$$

If the negated values of the input variables present at inputs 45 e and f of one logic element are applied to inputs g and h , respectively, the element serves as a half adder (modulo-2 addition), e.g., $s = (X \vee Y) \cdot (\bar{X} \vee \bar{Y}) = XY \vee \bar{X}\bar{Y}$; correspondingly, $\bar{s} = \bar{X} \cdot \bar{Y} \vee XY$.

50 These different logic possibilities are fully utilized in the circuit of FIG. 6. Thus, the logic element 11 provides the modulo-2 sum between Y and Z. This sum, as well as the input value X, is added to the logic element 12 which furnishes at its output the modulo-2 sum of all three input values X, Y and Z, which is then transferred to the output R. The logic element 55 14, in the same manner, receives as one input value the output value from the logic element 12 and as a second input variable the value c, which it adds by modulo-2 addition to produce the dual sum S. To the input of logic element 13 the negated values of input values X, Y, Z are applied as $\bar{X}, \bar{Y}$ and $\bar{Z}$ as well 60 as the negated output value $\bar{s}_1 = \bar{Y}\bar{Z} \vee YZ$ from logic element 11. The output values from logic element 13 are then

$$s_3 = (\bar{X} \vee \bar{s}_1) \cdot (\bar{Y} \vee Z) = \bar{X}\bar{Y} \vee XZ \vee YZ$$

and

$$\bar{s}_3 = XY \vee XZ \vee YZ,$$

65 $\bar{s}_3$ being brought to output T.

The equation for output C of unit 15 is:

$$C = c(X \oplus Y \oplus Z) \vee (\bar{X} \oplus \bar{Y} \oplus \bar{Z}) (XY \vee XZ \vee YZ).$$

The negated values of the first and of the second parenthetical 70 terms are available at the outputs s_2 and $\bar{s}_2$ of logic element 12 and that of the third parenthetical term at output s_3 . These, as well as the negated value of the input value c, are correspondingly brought to logic element 15.

In detail, the logic description of the modular unit 1 is as follows:

$e_1=Y$	$f_1=Z$	$g_1=\bar{Y}$	$h_1=\bar{Z}$
$e_2=s_1$	$f_2=X$	$g_2=s_1$	$h_2=\bar{X}$
$e_3=\bar{X}$	$f_3=\bar{s}_1$	$g_3=\bar{Y}$	$h_3=\bar{Z}$
$e_4=s_2$	$f_4=c$	$g_4=s_2$	$h_4=c$
$e_5=c$	$f_5=s_2$	$g_5=s_2$	$h_5=s_3$
$R=s_2$	$S=s_4$	$T=s_3$	$C=s_5$
$\bar{R}=s_2$	$\bar{S}=s_4$	$\bar{T}=s_3$	$\bar{C}=s_5$

The modular unit 1 created according to the present invention is distinguished by its minimum cost, which is made possible by its versatile utilization of the same logic elements, and it is also quite economical since it consists only of one type of logic element. In addition, the unit is characterized by a compact construction due in substantial part to the series connection of logic elements 11, 12 and 14, which is in turn made possible by the associative behavior of modulo-2 addition.

Circuits 2a, 2b and 2c are also each formed by one of the above-described known logic elements. The inputs e and h are used as control inputs and an input variable and its negated value are applied to inputs f and g , respectively. If one considers the appropriate logic input variable as LX , the following dependence of the output value of the logic elements on the control of inputs e and h results:

e	h	s	$\bar{s}$
0	0	0	1
0	1	LX	$\bar{LX}$
1	0	$\bar{LX}$	LX
1	1	1	0

The outputs from the logic element thus have the values 0 and 1 or LX and $\bar{LX}$, depending on how they are controlled. For the logic element 2a, $LX=X', \bar{LX}=\bar{X}'$. For the logic element 2b, $LX=Y', \bar{LX}=\bar{Y}'$, and for the logic element 2c, $LX=Z', \bar{LX}=\bar{Z}'$. The inputs e , h and f , g can be interchanged while retaining the above-mentioned functions.

The novel use of the logic elements as input control elements according to the present invention, i.e., as circuits 2a-2c, thus makes it possible to construct the entire unit 2 of one type of logic element so that unit 2 is distinguished by very low cost in addition to the earlier-listed functional advantages. It is particularly suited for utilization as a modular unit in monolithically integrated circuitry.

FIG. 7 shows a known embodiment (Motorola MECL) of the known logic element. The circuit consists of two transistorized sum-and-difference amplifiers 51 and 52, each of which receives two inputs and which together achieve the function $s=e \cdot f \cdot g \cdot h$, and of a multiple-emitter transistor 52 having a suitable operating voltage U_H applied to its base to produce the function $s=(e \cdot f) \cdot (g \cdot h)$. An emitter follower stage is connected to each sum-and-difference amplifier as well as to the multiple-emitter transistor.

It will be understood that the above description of the present invention is susceptible to various modifications, changes and adaptations, and the same are intended to be comprehended within the meaning and range of equivalents of the appended claims.

We claim:

1. A modular circuit unit having four inputs X , Y , Z and c and corresponding negated inputs $\bar{X}$, $\bar{Y}$, $\bar{Z}$ and $\bar{c}$, and having four outputs, R , S , T and C and corresponding negated outputs $\bar{R}$, $\bar{S}$, $\bar{T}$ and $\bar{C}$, said unit comprising five identical logic elements each having four inputs e , f , g and h and two outputs s and $\bar{s}$, where $\bar{s}$ is the negated value of s , each said logic element constituting means for producing the following relationships:

$$s = (e \vee f) \cdot (g \vee h)$$

$$\bar{s} = (e \bar{f}) \vee (\bar{g} \bar{h})$$

said logic elements being connected to each other and to said inputs X , Y , Z and c and said outputs R , S , T and C , as well as to negated inputs $\bar{X}$, $\bar{Y}$, $\bar{Z}$ and $\bar{c}$ and negated outputs $\bar{R}$, $\bar{S}$, $\bar{T}$ and $\bar{C}$, in the following manner, wherein each subscript represents a respective logic element:

$e_1=Y$	$f_1=Z$	$g_1=\bar{Y}$	$h_1=\bar{Z}$
$e_2=s_1$	$f_2=X$	$g_2=s_1$	$h_2=\bar{X}$
$e_3=\bar{X}$	$f_3=\bar{s}_1$	$g_3=\bar{Y}$	$h_3=\bar{Z}$
$e_4=s_2$	$f_4=c$	$g_4=s_2$	$h_4=c$
$e_5=c$	$f_5=s_2$	$g_5=s_2$	$h_5=s_3$
$R=s_2$	$S=s_4$	$T=s_3$	$C=s_5$
$\bar{R}=s_2$	$\bar{S}=s_4$	$\bar{T}=s_3$	$\bar{C}=s_5$

2. An arrangement as defined in claim 1 further comprising at least one input unit constituted by a logic element identical with each of said logic elements, said input unit having two outputs s and $\bar{s}$ which present one of the sets of inputs X , $\bar{X}$ or Y , $\bar{Y}$ or Z , $\bar{Z}$, said input unit further having a first pair of inputs e and h and a second pair of inputs f and g , said input e being connected to receive a binary information bit, said input h being connected to receive the negated value of such binary information bit, and said inputs f and g being connected to receive binary control signals whose values cause each of said outputs to present such binary information bit in direct or negated form or to present a binary value which is independent of the binary information bit.

3. An arrangement as defined in claim 1 further comprising at least one input unit having a signal input, a control input, and a signal output connected to provide one of said inputs X , Y and Z , said input unit being arranged to deliver to its said output either the binary signal appearing at its said signal input, directly or in negated form, or a binary "1" or "0," independent of the signal appearing at its said signal input, under the control of the signal applied to its said control input.

4. An arrangement as defined in claim 3 connected to act as an arithmetic circuit for the i th bit location of an n -bit arithmetic unit.

5. An arrangement as defined in claim 4 wherein there are n of said arithmetic circuits, the i th one of said circuits being associated with a respective i th bit location of said arithmetic unit.

6. An arrangement as defined in claim 5 wherein said arithmetic unit further comprises operand storage registers D , A , B , U and V each having $n+1$ bit locations, and each said logic unit is provided with three input units each connected to provide a respective one of said inputs X , Y and Z , the signal inputs to said input units being designated X' , y' and z' , respectively, and wherein, for the i th arithmetic circuit:

said signal input X' is connected to the i th bit location output of said storage register D ;

said signal input Y' is connected to the i th bit location output of said register A ;

said signal input Z' is connected to the i th bit location output of said register U ;

said input c is connected to the output C of that one of said circuits provided for the next lower bit location ($i-1$) of said arithmetic unit;

said output R is connectable to the $(i-1)$ th bit location input of said register B ;

said output S is connectable to the i th bit location input of said register B ; and

said output T is connectable to the i th bit location input of said register V .

7. An arrangement as defined in claim 6 further comprising, in order to eliminate the need for transferring stored values from one of said registers to another during multistep arithmetic operations, switching means connected between said registers A , B , U and V and each said arithmetic circuit, said switching means being arranged for alternately connecting:

said output R of said i th arithmetic circuit to the $(i-1)$ th bit location input of either said register B or said register A ;

said output T or said i th arithmetic circuit to the i th bit location input of either said register V or said register U ;

the Y' input of said i th arithmetic circuit to the i th bit location output of either said register A or said register B ; and

the input Z' of said i th arithmetic circuit to the i th bit location of either said register U or said register V ; and wherein said switching means are controlled for causing each said register to be connected only to inputs or to outputs of said arithmetic circuits at any given time.
